UNITED STATES PATENT OFFICE.

JOHN A. DE VILBISS AND HENRY L. MILLER, OF ST. LOUIS, MISSOURI; SAID DE VILBISS
ASSIGNOR OF HIS RIGHT TO GEORGE F. ERNST, OF ST. LOUIS, MISSOURI.

INTENSIFIER FOR SPARK-PLUGS.

1,335,940.

Specification of Letters Patent.

Patented Apr. 6, 1920.

Application filed April 5, 1919. Serial No. 287,879.

To all whom it may concern:

Be it known that we, JOHN A. DE VILBISS and HENRY L. MILLER, citizens of the United States, residing in the city of St. Louis, State 5 of Missouri, have invented a certain new and useful Improvement in Intensifiers for Spark-Plugs, of which the following is a full, clear, and exact description, such as will enable others skilled in the art to which 10 it appertains to make and use the same.

This invention relates to intensifiers for spark plugs of internal combustion engines.

The main object of our invention is to provide an intensifier that can be placed directly 15 on top of the spark plug with which it is used, thereby eliminating all separate attaching devices, and also having the intensifier in such a position that it will be subjected to the least vibration when the 20 engine is in operation.

Another object is to provide an intensifier that is small and compact, neat in appearance and which can be manufactured and sold at a low cost.

25 Still another object is to provide an intensifier that is provided with integral means in the interior thereof for attachment to a spark plug. Other objects and desirable features of our invention will be here- 30 inafter pointed out.

Figure 1 of the drawings is a perspective view of an intensifier constructed in accordance with our invention, showing the same attached to a spark plug.

35 Fig. 2 is a vertical sectional view of said intensifier; and

Fig. 3 is a detail view, illustrating a different method from that shown in Figs. 1 and 2 for attaching the intensifier to the 40 spark plug.

Referring to Figs. 1 and 2 of the drawings which illustrate the preferred form of our invention, A designates the body portion of our improved intensifier which is preferably 45 cylindrical and formed of fiber or other suitable insulating material, and B and B' designate cap pieces which inclose the upper and lower ends of said body portion, respectively, said cap pieces preferably having 50 their open ends turned or spun into slight grooves in said body portion, as shown at 1 in Fig. 2. Internally screw-threaded tubes 2 and 3 extend inwardly from the center of

said cap pieces B and B', respectively, said tubes being preferably, but not necessarily, 55 an integral part of said cap pieces, as shown clearly in Fig. 2. The tube 3 on the lower cap piece B' is provided with internal screw threads for the reception of the usual threaded stem 4 of a spark plug C, said tube being 60 of sufficient length that when it is in position on the plug, the stem 4 will not project above the upper edge thereof. A rod 5 is threaded into the tube 2 of the upper cap piece B, the lower end of said rod being 65 spaced away from the upper end of the tube 3, so as to provide a gap α across which the electrical spark of the intensifier jumps when the device is in operation. The rod 5, being threaded into the tube 2, is adjustable 70 vertically so as to vary the size of the spark gap α to suit different engine conditions, and a lock nut 6 is provided to hold said rod in adjusted position, the upper end of said rod extending upwardly beyond said cap 75 piece to form a binding post for the usual electrical terminal (not shown).

In order to see the lower end of the rod 5 and the upper end of the tube 3 and to enable the gap α formed therebetween to be 80 accurately adjusted, we provide a pair of oppositely-disposed sight openings 7 in the body portion A at a point substantially in alignment with said gap α , and a transparent member 8, preferably a sleeve formed of 85 mica or other suitable material is placed over the inside of said openings so as to protect the interior of the intensifier.

In the majority of instances, the intensifier can be screwed directly onto the usual 90 threaded stem 4 of a spark plug, thereby eliminating separate connecting devices and relieving the intensifier of any undue vibration which would occur if the intensifier were placed at one side of the plug and 95 connected thereto by a thin brass terminal, as is the usual practice.

In some cases an engine is so designed that the intensifier cannot be placed in a vertical position on the plug, and also 100 in some instances the diameter of the stem 4 of the spark plug may be slightly different from the diameter of the threads in the tube 3. In such cases we provide an adapter D which consists of a threaded stem 9 that 105 fits in the tube 3 and an eye 10 that slips

over the stem 4 of the spark plug, a nut 11 being screwed onto said stem to hold said adapter in position. The intensifier is then supported in a substantially horizontal 5 position at one side of the spark plug, as shown clearly in Fig. 3.

It will be obvious that when the device is in operative position on a spark plug and the usual electrical connections are applied, 10 that the electric current passing through the rod 5 will be forced to jump the gap α before jumping the usual gap between the contacts c' of the spark plug, thus greatly intensifying the spark produced at said contacts. 15

An intensifier of the construction above described is small, light and compact and comprises only a few simple parts which can be manufactured and assembled cheaply 20 and sold at a comparatively low price. By placing the intensifier directly on the stem 4 of the spark plug, vibration is reduced to a minimum and the life of the intensifier is consequently greatly prolonged. The spark 25 gap α of the intensifier can be easily varied to obtain the best results, while the engine is in operation, by turning the rod 5 in one direction or the other and observing the result through the sight openings provided 30 in the body portion.

Having thus described our invention,

what we claim and desire to secure by Letters Patent, is:

1. An intensifier for spark plugs, comprising a body portion provided on its interior 35 with a spark gap, and a threaded tube in said body portion, the upper end of which forms one side of said gap and the lower end of which is adapted to be threaded directly onto a spark plug. 40

2. An intensifier for spark plugs, comprising a body portion of insulating material, cap pieces at each end thereof having inwardly-projecting, internally-threaded extensions, and an adjustable rod in one of 45 said extensions having its lower end spaced away from the upper end of the other extension so as to form a gap therebetween.

3. An intensifier for spark plugs, consisting a body portion comprising a sleeve of 50 insulating material, cap pieces on each end of said sleeve, internally-threaded tubes extending inwardly from the center of each of said cap pieces, an adjustable rod mounted in one of said tubes, means for locking said 55 rod in adjusted position, sight openings in said body portion substantially in alignment with the lower end of said rod, and a transparent cover for said openings.

JOHN A. DE VILBISS.

HENRY L. MILLER.
